UNITED STATES PATENT OFFICE.

BENJAMIN SCHWARTZMAN, OF NEW YORK, N. Y., ASSIGNOR TO RELIANCE METAL SPINNING COMPANY, OF NEW YORK, N. Y., A COPARTNERSHIP CONSISTING OF SAMUEL SHAPIRO, JOSEPH SHAPIRO, SOLOMON SHAPIRO, DAVE SHAPIRO, AND MORRIS BERMAN.

DESIGN FOR AN ELECTRIC-LIGHT CASING.

48,532.

Specification for Design.

Patented Feb. 8, 1916.

Application filed September 16, 1915. Serial No. 51,106. Term of patent 7 years.

To all whom it may concern:

Be it known that I, BENJAMIN SCHWARTZMAN, a citizen of the United States, residing in the city of New York, borough of Brooklyn, in the county of Kings and State of New York, have invented a new, original, and ornamental Design for Electric-Light Casings, of which the following is a specification, reference being had to the accompanying drawing, forming part thereof.

Figure 1 is a side view of an electric light casing, showing my new design; Fig. 2 is a top view of the design shown in Fig. 1.

I claim:—

The ornamental design for an electric light casing, as shown.

BENJAMIN SCHWARTZMAN.
